 Angeles, Calif.

Application February 18, 1948, Serial No. 9,150

5 Claims. (Cl. 171—97)

1

This invention relates in general to remote control devices and the present application is somewhat related to my co-pending application for Automatic impulse timer and control circuit, Serial No. 722,355, filed January 16, 1947, now abandoned. More specifically, my invention pertains to a remote control unit comprising an actuating device or transmitter which momentarily introduces a unidirectional current, such as a pulsating direct current, into a line circuit in which alternating current is normally flowing as, for example, an alternating current power line, and a responsive device or receiver which receives the unidirectional current component in the line and is controlled thereby.

It is a primary object of my invention to provide a remote control unit which utilizes an alternating current line, for example, the conventional two-conductor, 110 volt house line, as a medium for the transmission of a pulsating direct current from the actuating device to the responsive device of such unit, without affecting the operation of various alternating current devices which may be connected to such line and drawing current therefrom.

It is an additional object to provide in such a unit an actuating device and a responsive device both of which are connected across the alternating current line to operate in parallel with the alternating current power source, thus eliminating the necessity of breaking the alternating current line for the purpose of placing either the transmitter or receiver in series therewith. In this connection, it is a further object to provide actuating and responsive components which may be plugged into the conventional outlet of an alternating current house line and operate therefrom.

It is a further object to provide a transmitter for such a unit which rectifies alternating current from the line to provide the unidirectional current which controls the receiver, thereby drawing all power for the operation of the unit from the alternating current line which serves as the transmission medium for the unidirectional current impulses.

It is a further object to provide a highly sensitive unit of this character so that the receiver may be controlled by the transmitter when separated an appreciable distance therefrom, as for example, when the receiver is plugged in at a second floor bedroom of a house and the transmitter is located in the first floor kitchen. It is an additional object to furnish sensitivity regulating means in conjunction with the receiver

2

whereby it is possible to selectively control one or more such receivers at varying distances from the transmitter without affecting another such receiver, as for example, a receiver located in a neighboring house, which although separated from the transmitter by isolation transformers may otherwise be responsive thereto.

It is an additional object to provide in an alternative embodiment shown, a transmitter which 10 selectively introduces into the line a pulsating direct current in either direction of flow and a receiver which is polarized so as to operate one load when such pulsating direct current is in one direction in the line and a separate load when 15 such current is in the opposite direction.

It is a further object to provide a compact and portable remote control device which is both simple and inexpensive to construct and requires no special installation for operation.

20 My invention achieves its objects by the use of a transmitter which includes a rectifier connected across the alternating current line and which is operative to load the line with a relatively small unidirectional current when its 25 switching means is closed. My receiver, which is likewise connected across the line, includes a relay in series with a sensitive, variable impedance current path. Normally, due to the magnitude of 30 this impedance, no appreciable flow of current across the line through the relay occurs. However, when a relatively small unidirectional current is introduced into the line by the transmitter, this high impedance current path is materially lowered and the relay actuated, which in 35 turn completes the circuit to the load.

In the alternative embodiment, the unidirectional current may be polarized in either direction by the transmitter and affects selectively 40 either of two variable impedances in the receiver 45 to actuate a switching relay controlling the circuit to two different loads.

Further objects of my invention will appear from the following specification and the drawing 45 which shows three embodiments of my invention for the purpose of illustration only and in which:

Fig. 1 is a circuit diagram of my remote control device connected in parallel with an alternating current power source through a two-conductor alternating current power line;

Fig. 2 is a similar circuit diagram showing an alternative embodiment of the receiver which includes a saturable reactor as a variable impedance means; and

Fig. 3 is a similar circuit diagram showing an

alternative embodiment for selectively controlling two separate loads.

Referring to Figs. 1 and 2 of the drawing, I show in each instance a two-conductor alternating current power line 11, carrying alternating power from a source, across which is connected an actuating device or transmitter including the components shown within the dotted line area indicated generally at 13.

In the dotted line area indicated generally at 14 there is shown a responsive device or receiver together with a load 30 which is controlled by the responsive device in the manner hereinafter described.

The transmitter 13 includes a half-wave rectifier 16 which is connected through a current-limiting resistor 17 to one side of the alternating current line 11 and through a switch 18 to the other side of the line 11.

The half-wave rectifier 16 may be any variety such as a mechanical, metallic or electronic valve, although I prefer to employ a metallic rectifier of copper oxide or selenium and I have found the latter particularly suitable for this use because of its ability to withstand relatively large momentary overloads. Since the rectifier 16, regardless of type, possesses negative resistance characteristics, the resistor 17, which, for example, may be a 50 watt, 10 ohm, D. C. resistor, is placed in series therewith to limit the current through the rectifier. For example, if a resistor 17 of the rating indicated above is used in conjunction with a $\frac{1}{2}$ ampere selenium rectifier 16, the unidirectional current across the line 11 will build up to a value of approximately 1 ampere on momentary closure of the switch 18, which current is ample to actuate the receiver 14 when the latter is separated a considerable distance from the transmitter.

Likewise, the switch 18 may be of any variety but I prefer to employ a through-type switch in order to prevent overload of the rectifier 16 in case of switch failure.

The receiver 14 shown in Fig. 1 includes a variable impedance circuit shown generally at 20 connected directly to the line 11 at one side and through a circuit closing relay 21 having a variable resistor 22 in parallel therewith, to the opposite side of the alternating current line 11. A load 30, represented for illustration as an incandescent lamp, is connected across the line 11 through the trip circuit of the relay 21, completing the circuit through the load when the relay armature 23 is positioned against the relay contact 24.

The variable impedance circuit 20 includes a capacitor 25 and an inductor 26 in parallel, forming a resonant circuit presenting a substantially infinite impedance to the flow of alternating current across the line 11 and through the relay 21. Although a fundamental or any low harmonic frequency of the alternating current in the line 11 may be selected with satisfactory results, I prefer to pretune the resonant frequency of the variable impedance circuit 20 to the second harmonic of the frequency of the alternating line current in order to obtain relatively high sensitivity to the unidirectional current from the transmitter 13 together with maximum impedance to the flow of alternating current across the line 11 when such unidirectional current component is not present. Thus, I have obtained excellent results when the line current was 60 cycle, for example, with the use of an inductor 26 of the iron-core type having an inductance of

4.5 henrys and a capacitor 25 of 4 microfarads, which together form a circuit resonant at about 38 cycles.

The relay 21 may be of varying sensitivity according to the contemplated distance of separation between the transmitter and receiver, the presence of intervening inductances, and the size of the variable resistor 22 shunting it. I have found, for example, that when the transmitter 13 and receiver 14 are both located within one conventional sized house with no intermediate isolation transformers in the line 11 between them, a relay 21 having a D. C. resistance of approximately 15 ohms and closing when a current of approximately .5 ampere flows through its coil circuit, is suitable. When such a relay 21 is shunted with a variable resistance 22 of, for example, 200 ohms D. C. resistance, a wide range of sensitivity adjustment is obtainable, permitting the selective operation of one or more of a plurality of receivers within a given building or distance. In the event operation between buildings through an interposed isolation transformer is desired, a more sensitive relay 21 and larger shunt 22 may be required.

Referring to Fig. 2, the circuit illustrated differs from that of Fig. 1 in the employment of a saturable reactor as the variable impedance circuit 20 comprising a control winding 28 and a controlled reactance 27. The latter is connected directly to one side of the alternating current line 11 and through the circuit closing relay 21 to the opposite side of the line. The control winding 28 is connected across the line 11 through the variable resistance 22.

The embodiment of my invention shown in Fig. 3 includes a transmitter shown generally at 33 having a pair of half-wave rectifiers 36 and 36a, each connected across the alternating current line 31 through the respective current-limiting resistances 37 and 37a and switches 38 and 38a. The half-wave rectifiers 36 and 36a are oppositely polarized, each permitting a flow of current in a counter direction to the other.

The receiver, including two loads 50 and 50a, is shown within the dotted line area indicated generally at 34. 51 and 51a are a pair of variable impedance circuits, the former, including an inductor 46 and a capacitor 45 in parallel therewith to form a resonant circuit, being connected across the line 31 through the coil 41 of a latching relay 49 and a variable resistance 42. The variable impedance circuit 51a includes a capacitor 45a and an inductor 46a in parallel therewith similarly connected through a variable resistance 42a and a relay coil 41a across the line 31. A half-wave rectifier 53 is interposed between the variable impedance circuit 51 and the relay coil 41 and similarly a half-wave rectifier 52 is connected between the variable impedance 51a and the relay coil 41a, but oppositely polarized to the half-wave rectifier 53.

The latching relay 49 has a common armature 43 which may pivot between contacts 44 and 44a to connect the load 50 or 50a respectively across the line 31. Relay latches 54 and 54a retain the armature 43 in closed or contact position after initial deflection and until the armature 43 is drawn by the coil 41 or 41a to the opposite position.

In operating the remote control device shown in either Fig. 1 or 2, the transmitter 13 and receiver 14 are connected to the line 11 by a conventional cord and plug (not shown) at some suitable location, each, for example, within sepa-

rate rooms of a house. The device to be controlled, for example a radio receiver connected to the line 11 in the usual manner, may contain an on-off switch or latching relay to be activated by a momentary electrical flow through the relay, or a latching relay may be included in the receiver itself in the manner illustrated in Fig. 3.

To actuate the remotely located device, the operator closes the switch 18 which causes a current to flow through the half-wave rectifier 16 and resistor 17 across the line. Such current flowing through the receiver 13 will be a pulsating direct current of a frequency one-half that of the alternating current in the line 11. I am of the opinion, although I do not wish to be bound thereby, that such unidirectional current acts upon the conventional alternating current in the line 11 to alter or distort the normal sine wave form of such current to an irregular wave having a diminished negative amplitude. In any event, the unidirectional current introduced into the line 11 materially lowers the impedance of the variable impedance circuit 20 of the receiver 14, permitting alternating current from the line 11 to flow through the relay 21 across the line 11.

In the device shown in Fig. 1 where the inductance 26 and the capacitor 25 are normally pretuned to a resonant frequency barring the flow of alternating current across the line 11, the unidirectional current introduced into the line by the transmitter has the effect of throwing this impedance circuit 20 off resonance, permitting the flow of alternating current through the relay 21. In the device illustrated in Fig. 2, but little current normally flows across the line 11 through the saturable reactor. In this circuit the introduction into the control winding 28 of the unidirectional current component radically reduces the impedance of the saturable reactor and similarly causes a current flow through the relay coil 21. In both instances, provided the sensitivity control, viz., the variable resistor 22, is properly adjusted, the current flow through the relay 21 will draw the armature 23 to the contact 24, completing the circuit to the load 30 or a suitable switching means in the device to be controlled.

In the embodiment shown in Fig. 3, the closure of the switch 38 will lower the impedance of the variable impedance circuit 51 to operate the relay 41 and load 50 in the manner indicated above, but will leave unaffected the variable impedance circuit 51a, due to the oppositely polarized half-wave rectifier 52. Similarly, the closure of the switch 38a will not affect the variable impedance circuit 51, since the unidirectional current thus introduced is blocked by the half-wave rectifier 53 from flow through this portion of the receiver 34 but load 50a will be actuated in the manner previously described. Thus, it is apparent that each switch 38 or 38a will affect only one of the loads 50 or 50a, respectively, to permit selective multiple control.

I have found that both variable impedance means illustrated and described above, namely, the resonant circuit and the saturable reactor, are extremely sensitive and will be affected by the unidirectional current from the transmitter at considerable distances therefrom. Moreover, I have, with the use of my invention, controlled receivers located within other buildings from that in which the transmitter is located, even in instances where an isolation transformer intervenes between the two. In order to regulate and decrease sensitivity and avoid undesired actua-

tion of any receiver by a foreign transmitter, I have provided a variable resistor 22 in the circuit shown in Fig. 1 which shunts the relay 21 to the extent desired to limit relay response to a current of a minimum magnitude. In the circuit illustrated in Fig. 2 the variable resistance 22 serves to limit, as desired, the flow of the unidirectional current through the control coil 28, thus varying the magnitude of the unidirectional current required to lower the impedance of the saturable reactor to the required degree. Similarly, in Fig. 3, the variable resistors 42 and 42a control the flow of the unidirectional current through the variable impedance circuits 51 and 51a, respectively.

I have also found that the operation of my receiver and transmitter does not affect the functioning of any other alternating current devices connected to the line and operating therefrom. In addition, both my receiver and transmitter contain no large or bulky components but each is capable of being housed in a small portable case for easy movement and connection to a line in a wide variety of useful locations wherever outlet plugs exist.

Although I have described my invention in connection with its use in a household to remotely control various electrical devices, wherein such operation may be from a conventional 110 volt, 60 cycle house current line, it is apparent to anyone skilled in the art that my invention is equally applicable to a wide variety of uses where multiple phase systems are employed or a less conventional type of alternating current power is supplied as, for example, 400 cycle alternating current. Moreover, my invention is useful in a wide variety of commercial and industrial applications as, for a single example, to fire photographic flash bulbs at a remote location therefrom by electrical means. Accordingly, such description is intended for illustrative purposes only and I do not wish to be limited thereby but wish to be accorded the full scope of the following claims.

I claim as my invention:

1. In an arrangement for energizing apparatus connected to an alternating current line through which alternating current is normally flowing by unidirectional current impulses: a circuit closing relay for completing the line circuit to the apparatus to be energized; and variable impedance means connected in series with said relay to provide electrical isolation of said relay from the alternating current in the line, said means comprising a saturable reactor responsive to the unidirectional current impulses to permit the flow of alternating current through said relay.

2. In a remote control unit for use in combination with an electrical alternating current supply line; an alternating circuit having a ground wire and a live wire, a transmitter including a half-wave rectifier, a switch means, and a resistor means in series and connected across the ground and live wires; a receiver including a variable impedance system having one end thereof connected to the ground wire and the other end thereof connected to the live wire, the system consisting of a tuned circuit in series with a parallel connected circuit having in one of its conductor paths the coil of a relay unit and in the other conductor path a resistor means.

3. The control unit recited in claim 2 wherein the rectifier is a selenium cell and the impedance is an induction coil having a rating of about 4.5 75 henrys and a condenser having a capacitance of

about 4 microfarads whereby the alternating current in the receiver is kept at an immaterial value but permitting direct currents from the transmitter to enter and operate the coil of the relay.

4. The control unit recited in claim 2 wherein the rectifier is a copper oxide pile and the receiver impedance a small tank circuit having an induction coil and a condenser, and a current load having one side thereof connected to the ground wire, a switch operable by the relay unit having one side thereof connected to the load and the other side thereof connected to the live wire.

5. In a direct current means for remotely controlling the operation of an electrical load; a pair of electrical conductors carrying alternating current, an electrical load having one electrical side thereof connected to one of the conductors and another electrical side thereof connected to one electrical side of a switch, and means connecting the other electrical side of the switch to the other one of said pair of conductors, a relay coil for operating the switch, and a resistor in parallel therewith forming a double electrical path, a tuned

current regulator in series connection with the mentioned double electrical path which provides a series-parallel hook-up, this hook-up having its ends electrically connected between the said pair of conductors; and a multiple connected rectifier, signal switch and resistor connected between the pair of conductors at some remote point thereof which causes electrical pulsations independent of the alternating current which pass through the conductors and through the relay coil to operate it when the signal switch is closed.
